UNITED STATES PATENT OFFICE.

DAVID S. ANTHONY, OF SAN ANTONIO, TEXAS.

BURR FOR GRISTMILLS.

Application filed June 17, 1925. Serial No. 37,783.

The object of my invention is to provide a burr for grist mills which may be quickly and cheaply resharpened so that the burr may be used a large number of times before it is worn out, the principal object of resharpening, however, being to economize in the power required to operate the burr, and also to produce a high grade flour.

My invention consists in the construction, 10 arrangement and combination of the various parts of the device, whereby the objects contemplated are attained, as hereinafter more fully set forth, pointed out in my claims, and illustrated in the accompanying drawings, in 15 which:

Figure 1 is a plan view of a segmental portion of my improved burr.

Figure 2 is a sectional view taken on the line 2—2 of Figure 1.

20 Figure 3 is a detail sectional view taken on the line 3—3 of Figure 1.

Figure 4 is an edge view of my improved burr.

25 Figure 5 shows a segmental portion of a slightly modified form.

Figure 6 is also a segmental portion of a further modification.

My improved burr comprises a body portion 10 which is in the form of a disk having 30 a central recess 11. The bottom end of the recess 11 terminates in an opening 12. The bottom face of the member 10 is provided with an annular groove 14 which serves to form a hub 15 on the lower end of the opening 12, and an annular rim 16 at the outer edge of 35 the member 10, the lower edge of the hub 15 and the rim 16 being in the same common plane so as to provide supporting portions for the burr.

40 To prevent the serrated surfaces of the co-acting burrs from engaging each other when running empty, or by careless adjustment of the same, I have provided an annular hub member 30 having a series of outwardly ex- 45 tending and curved blades 31 designed to rest on the upper edge of the hub member 15. Spaces are provided between the members 31 to permit material to enter the burrs. The outer face of the member 30 is finished and 50 extends a slight distance above the finished surface of the lugs 18, just enough to prevent the surfaces of the said lugs 18 from engaging the surface of the coacting burr, said surface being designed to engage one end of 55 the hub of said coacting burr.

The upper surface of the member 10 is pro-

vided with a series of triangular recesses 17 having their apex ends extending inwardly and their axis extending slightly tangent with the center of the member 10, the said 60 triangular recesses being so arranged that lugs 18 are provided. The inner ends of said lugs terminate in the inclined surface 13, while the outer ends terminate in the circumferential surface of the faces 10, while the 65 side members of the lugs 18 are parallel. These lugs 18 may be arranged with their longitudinal axis either radial or tangent with the center of the disk. The exact alignment of the said lugs being varied to suit the 70 working conditions, which will vary with the various kinds of flour to be milled and the different kinds of grain employed.

By this arrangement it will be seen that the top surface of all of the lugs 18 rest in a common plane parallel with the base portion of the members 15 and 16, so that the top faces of the lugs 18 may be finished by placing the member 10 in a lathe or suitable grinding 75 machine.

After the top surfaces of the members 18 have been finished, I then provide a series of cutting teeth 19 which are triangular in cross section, as illustrated in Figure 3. These teeth are cut longitudinally with the longitudinal axis of the lugs 18, all of the said 80 teeth being absolutely parallel with each other and extending from the outer end of said lug 18 to its inner end, and all of the teeth of each lug 18 being cut at the same time 85 and with a single tool, thereby materially reducing the first cost of the burr and also the cost of resharpening the same. By cutting the teeth 19 with a suitable tool in a planer or a milling machine, it is possible to produce very fine and sharp teeth, some of which 90 run as high as thirty-two to the inch.

After the teeth 19 have been cut into the surface of the lugs 18, I then place the burr under a grinder, which is in the form of a 100 thin disk, and grind radial grooves 20, starting at the inner ends of said lugs and grinding radially outwardly. These grooves 20 may be formed parallel with the teeth 19 or 105 may be formed slightly angular with said teeth. The grooves, however, are placed adjacent to the forward side of each of the lugs, so that as the burr is being operated in the direction indicated by the arrows in Figure 1, the material which is fed through the central openings 11 and 12 will work radially 110 outwardly through the grooves 20 and thence 116

is crushed and moves backwardly, outwardly and over the teeth 19, as indicated by the arrows, and into the recesses 17. The burr 10 is designed to coact with a plain burr which 5 is oppositely disposed and which has coacting teeth formed in a flat annular face.

Another form of my disc is illustrated in Figures 5 and 6. The said disc has an annular face designated by the numeral 21. 10 The said face is then provided with a series or group of radially arranged teeth 22, the teeth of each group being parallel with each other and formed with a single tool, as before described. A portion of the teeth of one 15 group may be made to intersect a portion of the teeth of the opposite group as indicated at 23.

If it is desired to place each group of teeth as close together as possible, the portion 23 20 provides means whereby a larger portion of the bran will be worked in the flour. Feed grooves 24 may then be ground in the surface 25 the same as for the burr 10. In Figure 5 I have shown the grooves 24 ground in between the portions 23, while in Figure 6 I have shown the said grooves 24 ground into the portions 23.

By the arrangement in Figure 5 it will be seen I have provided a comparatively large 30 area of the intersecting portion 23, while in Figure 6 I have cut away most of the said portion 23. The groups of teeth 22 may be so placed in the surface 21 that the inner ends of one group will simply adjoin the inner 35 ends of a second group, and thereby eliminate the portion 23 altogether, if so desired, similar to the manner illustrated in Figure 1, with the exception that the recesses 17 are not provided.

40 It will be seen that in these several constructions I have used one method of forming the teeth, which consists in the simplest form of providing an annular raised portion on one face of the disk, then cutting 45 groups of sharp teeth in said raised portion either radial or slightly tangent with the center of the disk, and cutting from one edge to the other of said annular portion, and then grinding into said toothed portions feed 50 grooves.

By this construction it will be seen that I have produced a burr which is very economical to build originally, and which is very accurate and adapted to produce a very fine 55 grade of flour, if so desired, due to the fact that all of the parts may be machined, and the coacting burrs will fit very closely, and are sharp.

By providing sharp teeth, I have been able 60 to reduce the amount of power required to operate the burrs about fifty percent over the ordinary burr which is provided with cast teeth. It will be seen that considerable advantage is gained by first forming the teeth 65 into the surface of the burr and then grind-

ing in the feed grooves, as the gang tool may be fed at a uniform depth as it moved across the surface of the burr, while if the feed grooves were cast into position before the teeth are formed, it will be seen that any pressure, applied to hold the tool into operation relative to the plate, is necessarily very high, due to the fact that the plates are formed of chilled or case hardened material. It will be seen that if a given pressure was applied 75 to the tool as it enters the outer end of the lugs 18 to form teeth of a given depth, then as the tool enters the portion 23 the same amount of pressure would be applied to a smaller area, and the tool would be caused 80 to cut the teeth deeper at their inner ends, while by cutting the teeth first, they will be formed of a uniform depth.

Furthermore, by grinding the grooves into 85 position, a stock casting may first be provided. The teeth and the grooves of one set of burrs may be ground at one angle relative to the radius, while another burr may be provided with grooves at a second angle relative to the radius.

90 It will further be seen that this also considerably reduces the cost of construction, and at the same time provides a feed groove which is smooth and permits the material to be readily fed into the teeth, while a cast 95 groove would be more or less rough and would somewhat hinder the outward movement of the material.

By forming a group of these teeth in a single 100 operation, I have greatly reduced the expense of forming the burr and also re-sharpening, thus enabling the operator to be able to afford to have the burrs resharpened as often as necessary, and at the same time produce a flour of very high grade.

105 I claim as my invention:

1. A burr for grist mills comprising a substantially disk shaped body portion, the upper face of said body portion being provided with a series of outwardly extending recesses 110 to form a series of outwardly extending lugs, the upper face of each of said lugs being provided with a group of outwardly extending teeth, the teeth of each group being parallel to each other and extending from the outer 115 to the inner end of said lug.

2. A burr for grist mills comprising a substantially disk shaped body portion, the upper face of said body portion being provided with a series of outwardly extending recesses 120 to form a series of outwardly extending lugs, the outer face of each of said lugs being provided with a group of radially arranged teeth, the teeth of each group being parallel to each other and extending from the outer 125 to the inner end of said lug, and a feed groove formed in the inner end of each of said lugs and extending into the said teeth.

3. A burr for grist mills comprising a body portion, said body portion being provided 130

with a lug, a group of teeth machined in said lug, the teeth of said group being formed parallel with each other and extending from one end of said lug to its opposite end.

5. 4. A burr for grist mills comprising a body portion, said body portion being provided with a lug, a group of teeth machined in said lug, the teeth of said group being formed parallel with each other and extending from 10 one end of said lug to its opposite end, a feed groove extending inwardly from one end of said lug into the center of each group of teeth.

5. A burr for grist mills comprising a body

portion substantially in the form of a disk, 15 one face of said disk being provided with an annular rim, the face of said rim being smooth and perpendicular to the center of said disk, a series of groups of teeth machined in said rim, the teeth of each group 20 being parallel to each other and extending from one edge of said rim to its opposite edge, a feed groove extending radially and longitudinally from the inner edge through a portion of each of said groups of teeth. 25

Des Moines, Iowa, June 3, 1925.

DAVID S. ANTHONY.
